CORN SHOCKER

Edward H. Rehn, Leelan E. Rehn, and Arnold M. Squire, Lima, Ohio

Application September 25, 1936, Serial No. 102,572
Renewed September 23, 1938

9 Claims. (Cl. 56—401)

This invention relates to a device for use in connection with binders for material such as corn to facilitate the binding of the material into shocks and the depositing of the shocks on the ground surface in an upright position.

An object of the present invention is to provide a device of the character mentioned which may be readily coupled to a corn binder or the like and which is characterized by simplicity of construction, ease of operation and otherwise capable of performing the function intended.

A further object of the invention is to provide a material shocking attachment which builds shocks in a horizontal plane and is used in connection with, or as an integral part of a material binder.

A further object of the invention is to provide a shocker which has a hopper to receive the material and also an elevator which receives the material from any suitable source and feeds it to the hopper.

The invention together with its objects and advantages will be best understood from a study of the following description taken in connection with the accompanying drawings wherein:

Figure 1 is a side elevational view of a shocker embodying the features of the present invention, and a portion of a conventional corn binder to which the shocker is hitched.

Figure 2 is a top plan view of the structure shown in Figure 1.

Figure 3 is a rear elevational view of the device.

Figure 4 is an enlarged sectional view taken through a portion of the hopper and

Figure 5 is a detail elevational view of the combination pivot and hinge joint for the hopper.

Referring to the drawings by reference numerals it will be seen that the shocking machine indicated generally by the reference numeral 5 comprises a frame 6 supported at one side thereof and adjacent its forward end through the medium of a wheel 7, and at a relatively opposite side thereof and adjacent its rear end through the medium of a wheel 8.

At its forward end the frame 6 is suitably provided as at 9 for coupling, as at 10, to the rear of a corn binder, indicated generally by the reference numeral 11, and only so much of which is shown and will be specifically referred to herein as is believed necessary for a clear understanding of the invention. Thus it will be seen that we have illustrated a corn binder of a well-known type, as for example, a type clearly shown in Patent No. 624,878, granted to C. S. Sharp,

under date of May 9, 1899, and which includes among other parts spring fingers or guides 11a, rotary ejectors 11b, rods 11c, and platform 11d, which are the parts which constitute the devices which deliver the corn stalks from the binder to the elevator 14 of the shocker, and which elevator will be hereinafter more fully referred to.

Also adjacent its forward end frame 6 is provided with a platform 12 or in any other suitable manner for catching the loose ears of corn that may drop from the bundles as they pass from the binder to the corn shocking machine.

Also suitably mounted on the frame 6 adjacent its forward end for receiving the bundles transferred from the binder 11 and for elevating the bundles to be dropped into a hopper or receptacle 13 is an elevator 14.

The elevator 14 may be of any suitable construction, in the present instance the same being shown as consisting of a frame 15 pivoted at its lower end as at 16 between brackets 17 rising from the frame. Also suitably journaled in the frame 15 are top and bottom rollers 18 over which are trained an endless belt or apron 19 provided with suitable prongs or the like 20 to engage the bundles for causing the latter to move upwardly with the elevator to discharge into the hopper 13.

For raising and lowering the elevator 14 there is suitably mounted on the frame 6 at one side thereof a stub shaft 21 that has an arm 22 extending therefrom and pivoted as at 23 to an arm 24 secured at one end to one side of the frame 15 of the elevator. Fixed relative to the shaft 21 is a rack segment 25 and cooperable with the rack segment for holding the elevator 14 at the desired position of angular adjustment is the detent provided on a hand lever 26 suitably connected with the shaft 21 for rocking the latter to raise and lower the elevator.

At the rear corner thereof and the side of the frame opposite to the wheel 8 the frame 6 is shaped as indicated at 27 to provide suitable clearance for the hopper 13 when the latter is tilted vertically or to the dotted line position shown in Figure 2 for emptying the hopper of the shocks.

For mounting the hopper 13 for swinging movement in a horizontal plane and for vertical tilting movement there is suitably mounted on the frame 6 adjacent the corner 27 thereof a short post 28 provided at its upper end with an enlarged head 29. Aligned with the post 28 is a relatively short post or pivot rod sections 30 provided at its lower end with a flange or head 31 seating on the flange or head 28. Embracing the pivot rod section 28, 30 at the flanged meeting ends thereof,

55

is a split internally grooved clamp 32 that serves to connect the pivot rod sections 28 and 30 in such a manner as to permit the section 30 to rotate relative to the section 28.

5 The hopper 13 is hinged to the pivot post section 30 and to this end the hopper 13 at the bottom thereof is provided with a boss 33 formed with a hinge leaf 34 while the pivot post section 30 is provided with an integral hinge leaf 35, 10 the leaf 34 and leaf 35 being connected together through the medium of a hinge pintle 36. It will thus be seen that the hopper 13 may be swung vertically relative to the post section 30 through the medium of the hinge just described. Thus 15 the hopper 13 is mounted to swing in a horizontal plane and to be tilted in a vertical plane.

The hopper 13 is also provided at one side thereof with a vertically swinging hinge door 37, suitable latch means 38 being provided for releasably 20 holding the door in closed or vertical position.

Also, in accordance with the present invention, suitable means may be provided for driving the elevator from the traction wheel 8 and to this end there is suitably mounted on the frame 25 a shaft 39 that is driven from the axis of the wheel 8 through a chain and sprocket connection 40. Also suitably mounted on the frame 6 is a shaft 41 which is driven from the shaft 39 through the medium of gearing 42. Shaft 41 in turn is 30 in driving connection with the lower roller 13 of the elevator 14 through the medium of a chain and sprocket means 43. Thus it will be seen that drive will be transmitted from the wheel 8 to the elevator 14 for operating the latter whereby 35 the bundles from the binder are conveyed to the hopper 13. When a sufficient number of bundles are deposited within the hopper these bundles are then tied together to form a "shock." In forming the shock the bundles are positioned within 40 the hopper so that the ends thereof to be placed on the ground surface abut the hinge door or wall 37 of the hopper.

When a shock has been made up in the hopper 13, the end door or wall 37 is dropped back clear 45 of the hopper. The hopper is then swung in a horizontal plane through an arc approximating 225° more or less, when the hopper is then tilted to the vertical position suggested by the broken line in Figure 2. The shock will then be discharged from the hopper 13 in a substantially 50 vertical position upon the ground and in such a location that the combination of binder and shocker can be drawn ahead and clear the shock.

It will be understood that when the hopper 13 is to be swung either to a position for dumping 55 the shock or back to its normal position for receiving the bundles from the elevator, the elevator is raised. To raise the elevator lever 26 is swung downwardly or in a counter-clockwise 60 direction and movement of the lever is transmitted through the arm 22 and link 24 to the frame of the elevator for causing the elevator to swing in a counter-clockwise direction so as to sufficiently clear the hopper or receptacle 13 leaving the same then free to be swung to a 65 dumping position and back to its normal position.

While, as far as the invention is concerned, it is immaterial the manner in which the corn stalks are placed on the elevator 14 of the shocker 70 it will be apparent, referring to the drawings, that when the shocker is used in connection with a type of harvester or corn binder illustrated, the spring guides 11a are curved out over the lower portion of the elevator 14 and the corn stalks 75 are forced between the spring guides by the ejec-

tors 11c. After a number of corn stalks have been fed to position, the ejectors 11b are tripped in the usual manner and rotate to force the corn stalks between the guide fingers 11a which in connection with the rod 11c act to turn the corn stalks so that they will fall across the elevator. The butts of the corn stalks rest upon the platform 11d which prevent the corn stalks from dropping and cooperates with the spring fingers 11a and the rod 11c to cause the corn stalks to be turned to a substantially horizontal position.

It is thought that a clear understanding of the construction, utility and advantages of an invention of this character will be had without a more detailed description.

While in the present case an elevator is employed for conveying the material to the shocking mechanism which is tilted to enable the hopper to clear the same when the hopper is swung to dumping position, we do not desire to limit ourselves to a tiltable elevator as other arrangements may be employed for permitting the discharge end of the elevator and the hopper to clear on the swinging movement of the hopper.

While the present machine has been described as particularly adapted for shocking corn stalks, it can be put to other useful purposes such as shocking stalks of sugar cane and Kaffir corn and for also shocking bundled hay of a certain variety and sunflowers as grown in some sections of the country, as well as other similar products.

Having thus described the invention what is claimed as new is:

1. A corn shocker embodying a wheel-supported frame, an elevator pivotally mounted on the frame, means connected with the elevator for raising and lowering the latter, and a hopper mounted on the frame to receive the bundles from the elevator, and means for mounting the hopper on the frame for swinging movement in a horizontal plane and for tilting movement in a vertical plane.

2. A corn shocker embodying a wheel-supported frame, an elevator pivotally mounted on the frame, means connected with the elevator for raising and lowering the latter, and a hopper mounted on the frame to receive the bundles from the elevator, and means for mounting the hopper on the frame for swinging movement in a horizontal plane and for tilting movement in a vertical plane, said means including a fixed pivot rod mounted vertically on the frame, a pivot rod section in alignment with the fixed rod section, means coupling the rod sections in a manner to permit the second rod section to rotate relative to the first rod section, and a hinge having a leaf integral with the second rod section and a second leaf integral with the second rod section and a second leaf integral with the bottom of said hopper.

3. A corn shocker embodying a frame, an elevator pivotally mounted on the frame, a shaft rotatably mounted on the frame, means operatively connecting the shaft with the elevator for raising and lowering the same, a hand lever connected with the shaft for rocking the latter, rack and detent means for holding the elevator at the desired adjustment, a hopper to receive the bundles from the elevator, a pivot rod for the hopper mounted on the frame and supporting the hopper for swinging movement in a horizontal plane, and hinge means operatively connecting the bottom of the hopper with the pivot rod in a manner to permit the hopper to swing vertically relative to the pivot rod.

4. In a shocker, a transportable frame, an elevator for the material to be shocked mounted on said frame and arranged to deliver the material rearwardly to the direction of travel of the frame, a hopper to receive the material from the discharge end of said elevator, the long axis of said hopper being arranged at right angles to the direction of travel of said frame, and a pivotal connection between the hopper and said frame such as to permit the hopper to be tilted to dump the load of material clear of the machine.
5. In a shocker, a transportable frame, an elevator for the material to be shocked mounted on said frame and arranged to deliver the material rearwardly to the direction of travel of the frame, a hopper to receive the material from the discharge end of said elevator, the long axis of said hopper being arranged at right angles to the direction of travel of said frame, and means for mounting the hopper on said frame such as to permit the same to be moved to a position to dump the load of material clear of the machine, said means including a pivoted support for said hopper such as to permit the hopper to be tilted.
- 10 6. In a shocker, a transportable frame, an elevator for the material to be shocked mounted on said frame and arranged to deliver the material rearwardly to the direction of travel of said frame, a hopper to receive the material from the discharge end of said elevator, the long axis of said hopper being arranged at right angles to the direction of travel of said frame, and means for mounting the hopper on said frame such as to permit the same to be moved in a position to dump the load of material therefrom clear of the machine including a pivoted support for said hopper the axis of which is arranged at an angle to the long axis of said hopper to permit the hopper to be tilted.
- 15 7. In a shocker, a wheel supporting frame, an elevator on said frame for the material to be shocked mounted on said frame and arranged to convey material in a direction rearwardly to the line of travel of said frame, a hopper on said frame to receive the material from the discharge end of said elevator, the long axis of the hopper
- being arranged at right angles to the direction of travel of said frame, means for mounting the hopper on said frame for a swinging movement in a substantially circular path, and a pivoted support for said hopper the axis of which is at 5 an angle to the long axis of the hopper to permit the hopper to be tilted.
8. A shocker embodying a wheel supporting frame, an elevator mounted on said frame arranged to deliver material in a direction rearwardly to the line of travel of said frame, a hopper on said frame to receive the material to be shocked from the discharge end of the elevator, the long axis of the hopper being arranged at 10 right angles to the direction of travel of said frame, means for mounting the hopper on the frame for swinging movement in a circular path and for tilting movement including a pivoted support for the hopper the axis of which is arranged at an angle to the long axis of said hopper, and 15 means for adjusting the relative positions of the discharge end of the elevator and the receiving portion of the hopper to provide a clearance when the hopper is swung in a circular path.
- 20 9. The combination, with a corn binder, of a 25 corn shocker comprising a wheeled frame, an elevator for the stalks of corn mounted on said frame and a hopper mounted on said frame to receive the stalks of corn from the discharge end of the elevator, said elevator being arranged to 30 deliver material rearwardly to the direction of travel of said frame and adapted to convey the stalks of corn to the hopper with their lengths at right angles to the direction of travel of the frame, the long length or axis of said hopper 35 being arranged at right angles to the direction of travel of said frame so as to receive the stalks of corn lengthwise therein, means for mounting the hopper on said frame to permit the hopper to be moved to a position to be dumped, and a 40 pivoted support for said hopper, the axis of which is at an angle to the long axis of said hopper to permit the hopper to be tilted.
